United States Patent Office.

ALONZO HEBBARD, OF NEW YORK, N. Y., ASSIGNOR TO EDWARD CORNING,
OF SAME PLACE.

Design No. 3,053, dated May 26, 1868.

DESIGN FOR A SPOON OR FORK-HANDLE.

The Schedule referred to in these Letters Patent and making part of the same.

TO ALL WHOM IT MAY CONCERN:

Be it known that I, ALONZO HEBBARD, of the city, county, and State of New York, have invented or produced a new and Ornamental Design or Pattern for Spoons, Forks, and other articles of tableware or cutlery; and I do hereby declare that the following is a full description of the same, reference being had to the accompanying drawings, forming a part of this specification, the same letters of reference, wherever they occur, referring to like parts.

Figure 1 is a front view of the spoon.

Letter A represents the bowl or blade of the spoon. B is the stem or handle of the spoon, the sides of which are sexagonal in form. At or near its junction with the bowl are formed circular collars, c, d, and e, of which the middle one, d, is a little larger in diameter than the others, and has a gnarled edge, and at its upper end, at its junction with the head of the handle, a similar gnarled collar, f, supported on either side by circular collars, g and h. Surmounting the end of the stem is a dome-shaped head or capital, J, having two thin bands, K, around its base, and the intervening space between them subdivided into numerous vertical lines, L. Underneath the lower band is formed a collar, m, having its edge gnarled, so as to form a bead-like base for the support of the dome and connection with the stem. Surrounding the dome is a gnarled-edged button, n, which is finished or surmounted by a small bead-like head, p, to complete the general design of the spoon.

Having now described my invention, I will proceed to set forth what I claim and desire to secure by Letters Patent of the United States.

I claim the design for the handle of a spoon, fork, &c., as described and shown.

ALONZO HEBBARD.
